(74) *Attorney, Agent, or Firm*—Stephen D. Carver

(57) **CLAIM**

The ornamental design for a vacuum island for car wash installations, as shown and described.

DESCRIPTION

FIG. 1 is a frontal isometric view of a preferred embodiment of my invention;

FIG. 2 is a rear isometric view of the first embodiment;

FIG. 3 is a top plan view of the first embodiment;

FIG. 4 is a front elevational view of the first embodiment, the rear view comprising a mirror image thereof;

FIG. 5 is a left end elevational view of the first embodiment, the right end comprising substantially a mirror image thereof;

FIG. 6 is a bottom plan view of the first embodiment thereof;

FIG. 7 is a frontal isometric view of a second embodiment of my invention;

FIG. 8 is a rear isometric view of the second embodiment;

FIG. 9 is a top plan view of the second embodiment;

FIG. 10 is a front elevational view of the second embodiment, the rear view comprising a mirror image thereof;

FIG. 11 is a left end elevational view of the second embodiment, the right end comprising substantially a mirror image thereof;

FIG. 12 is a bottom plan view of the second embodiment thereof;

FIG. 13 is a frontal isometric view of the third embodiment of my invention;

FIG. 14 is a rear isometric view of the third embodiment;

FIG. 15 is a top plan view of the third embodiment;

FIG. 16 is a front elevational view of the third embodiment, the rear view comprising a mirror image thereof;

FIG. 17 is a left end elevational view of the third embodiment, the right end comprising substantially a mirror image thereof; and,

FIG. 18 is a bottom plan view of the third embodiment thereof.
